UNITED STATES PATENT OFFICE.

RICHARD LUKE, OF CHICAGO, ILLINOIS, ASSIGNOR TO THE SENG COMPANY, OF CHICAGO, ILLINOIS, A CORPORATION OF ILLINOIS.

CRIB-HOOK.

971,058.

Specification of Letters Patent. Patented Sept. 27, 1910.

Application filed May 6, 1910. Serial No. 559,798.

To all whom it may concern:

Be it known that I, RICHARD LUKE, a citizen of the United States, residing at Chicago, in the county of Cook and State of Illinois, have invented a certain new and useful Crib-Hook, of which the following is a specification.

The invention relates to crib hoops adapted to hold the sliding sides of a safety crib in elevated position, and is adapted to automatically disengage said sliding sides to allow the same to be lowered.

The object of the invention is to provide a crib hook which will hold the sliding side of a crib in the elevated position and which may be automatically opened to allow the side of the crib to be lowered.

A further object of the invention is to provide a hook of this character whereby the side of the crib may be easily operated with one hand.

A still further object is to provide a hook of this character comprising two interlocking hooked members, so arranged that if one of the hooked members should accidentally disengaged, the other still remains in engagement with the side of the crib.

These and other objects are attained by means of the mechanism illustrated in the accompanying drawing, in which—

Figure 1 is a perspective view of a crib provided with the improved crib hook; Fig. 2, a side elevation of the crib hook showing the members in closed position; Fig. 3, a view similar to Fig. 2 showing the members in open position; Fig. 4, a sectional view taken on line 4—4 of Fig. 2; Fig. 5, a view similar to Fig. 4 showing a similar modification of the device; and Fig. 6, a side elevation of a still further modification.

Similar numerals refer to similar parts throughout the drawing.

This device is to be used upon cribs known as safety cribs, which are provided with sliding sides adapted to be raised and lowered. The crib shown in Fig. 1 is of this character, and is provided with the sliding sides 2 and 3. The side 2 is shown lowered and the side 3 is in raised position and engaged by the crib hooks 4. The sides 2 and 3 are slidably mounted upon the guide rods 5, and are provided with the projecting pins 6 located at the ends of the top bar of said slid-

ing sides. The said projecting pins 6 are adapted to engage the crib hooks 4 when the side is raised.

The crib hook is composed of two similar legs 7 pivotally connected near their upper ends as at 8, and provided with the feet 9 upon their lower ends. The heels of the feet 9 are overlapped and hooked to form the recesses 10 upon their upper edges, which recesses form the aperture 11, for receiving the projecting pins 6 of the sliding side, when the hook is in closed position. The lower edges of the feet 9 are inclined upward and inward as at 12. The legs 7 are provided, directly above the recess 10, with the inwardly-extending cusps 13. The upper and lower edges of each cusp 13 are inclined outward and the inner ends of said cusps 13 are overlapped.

Each of the legs 7 is provided with a recess 14 located between said cusps 13 and the pivotal point 8. When the hook is in its closed position, the said recesses 14 form an aperture 15 directly above the cusps 13. The legs 7 are preferably pivoted together by means of an eyelet 16 provided with the external annular flanges 17 upon its outer ends for retaining the legs in place thereon. One of the legs 7 is provided with the lug 18 upon its upper end and the other leg is provided with the lateral tongue 19 adapted to engage the lug 18 when the hook is in its closed position, and thereby limit the closing of the hook. The lateral tongue 19 is also adapted to engage the edge of the opposite hook when in the open position, thereby limiting the opening of the hook.

In Fig. 5, is shown a slight modification of the crib hook. In this form of the device, the leg 7' is provided with a flange 20 which projects through the opposite leg and is externally flanged as at 21, so as to hold the two legs together.

In Fig. 6, is illustrated a still further modification in which the ears 13 and notches 14 are not used.

The operation of the device is as follows: When it is desired to secure one of the sliding sides of the crib in its raised position, said sliding side is raised until the projecting pins 6 come into contact with the inclined lower edges of the feet 9. As the projecting pins 6 are still further raised, they press

upon the inclined edges 12 of the feet 9 and force the legs 7 apart and enter the apertures 11, whereupon the legs 7, being released, drop to their normal position and by the mutual interlocking of the hooked heels securely retain the projecting pins 6. In order to disengage the sliding side so that it may be lowered, it is first raised slightly so that the projecting pins 6, bearing upon 10 the lower edges of the cusps 13, force the legs 7 apart and allow the projecting pins 6 to pass on into the aperture 15. The sliding side is then moved downwardly, the projecting pins 6 bearing upon the upper edges 15 of the cusps 13 and again forcing the legs 7 apart and allowing the crib side to drop so that the projecting pins 6 are clear of the hooked heels of the feet 9 before the legs 7 drop to their normal position; especially if 20 the side is dropped quickly, or is accelerated by a slight pressure. It is evident that a single leg with a reversely inclined cusp between the hooked heel and the pivoted end can be used, but it is preferred to use two legs for more positive and interlocking action.

I claim:

1. A crib hook having a pivot support at its upper end, an inclined foot having a 30 hooked-heel on its lower end, and a cusp on the heel edge intermediate the hook and the pivot end.

2. A crib hook comprising two legs pivoted together at their upper ends, inwardly-hooked mutually-interlocking heels on their 35 lower ends, and means for limiting the opening and closing of the legs.

3. A crib hook comprising two legs pivoted together at their upper ends, inclined 40 feet on their lower ends and having mutually interlocking hooked-heels forming recesses in the inner edges of the legs above the feet, and means for limiting the opening and closing of said legs.

4. A crib hook comprising two legs pivoted together at their upper ends, inclined feet on their lower ends and having mutually interlocking hooked-heels with a recess in the inner edge of each leg forming 50 an aperture above the feet when the legs are closed.

5. A crib hook comprising two legs pivoted together at their upper ends, inclined feet on their lower ends and having mutually interlocking hooked-heels on their 55

inner edges, with cusps on the inner edges intermediate the hooks and the pivot ends.

6. A crib hook comprising two legs pivoted together at their upper ends, inwardly-hooked mutually interlocking heels on their 60 lower ends, with cusps on their inner edges intermediate the hooks and the pivot ends forming intervening recesses above and below the cusps.

7. A crib hook comprising two legs pivoted together at their upper ends, inclined feet on their lower ends and having mutually interlocking hooked-heels on their inner edges, with cusps on the inner edges intermediate the hooks and the pivot ends forming intervening recesses above and below the 70 cusps.

8. A crib hook comprising two legs pivoted together at their upper ends, inclined feet on their lower ends and having mutually interlocking hooked-heels on their inner edges, with cusps on the inner edges intermediate the hooks and the pivot ends, and means for limiting the opening and closing 75 of the legs.

9. A crib hook comprising two legs pivoted together at their upper ends, inwardly-hooked mutually interlocking heels on their lower ends, with cusps on their inner edges intermediate the hooks and the pivot ends 80 forming intervening recesses above and below the cusps, and means for limiting the opening and closing of the legs.

10. A crib hook comprising two legs pivoted together at their upper ends, inwardly-hooked mutually interlocking heels on the lower ends, a lug on the upper end of one leg and a lateral tongue on the upper end of the other leg adapted to engage the lug and the edge of the one leg to limit the opening 90 and closing of the legs.

11. A crib hook comprising two legs pivoted together at their upper ends, inclined feet on their lower ends and having mutually interlocking hooked-heels on their inner 100 edges, a lug on the upper end of one leg and a lateral tongue on the upper end of the other leg adapted to engage the lug and the edge of the one leg to limit the opening and closing of the legs.

RICHARD LUKE.
